UNITED STATES PATENT OFFICE.

LOUIS KESSLER, OF CHICAGO, ILLINOIS, ASSIGNOR TO NON-EXPLOSIVE CAN AND TUBE COMPANY, OF CHICAGO, ILLINOIS, A CORPORATION OF ILLINOIS.

FILLER-TUBE AND CLOSURE THEREFOR FOR RECEPTACLES.

1,312,695.

Specification of Letters Patent.

Patented Aug. 12, 1919.

Application filed June 23, 1916. Serial No. 105,390.

To all whom it may concern:

Be it known that I, LOUIS KESSLER, a citizen of the United States, residing at Chicago, in the county of Cook and State of Illinois, have invented certain new and useful Improvements in Filler-Tubes and Closures Therefor for Receptacles, of which the following is a description.

My invention belongs to that general class of devices known as filler tubes, and particularly relates to an improved tube and closure for the same. The invention has among its objects the production of a device of the kind described that is safe, simple, efficient, durable, compact and satisfactory for the purpose, which may be used wherever found applicable. The invention has particularly among its objects the production of a closure that may be used in connection with any suitable form of filler tube or filling opening of a receptacle for closing the opening where the tank is filled, whereby excessive pressure in the tank may be relieved, and where as the contents of the tank are drawn off air may be admitted to fill the space formerly occupied by the liquid. The creating of a vacuum in the tank, and consequent impairing of the discharge is prevented, and at the same time the escape of gas from the tank due to evaporation, is prevented. Other objects and advantages of the construction herein set forth will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts,

Figure 1 is a sectional view taken substantially on line 1—1 of Fig. 3.

Fig. 2 is a sectional view taken substantially on line 2—2 of Fig. 1;

Fig. 3 is a sectional view taken substantially on line 3—3 of Fig. 1;

Fig. 4 is a sectional view taken substantially on line 4—4 of Fig. 1, and

Fig. 5 is a sectional view taken substantially on line 5—5 of Fig. 1.

Referring to the drawings, 1 is a tube of suitable material provided with an extending flange 2 at the upper end, formed integral therewith, if desired, the same being suitably formed in any desired manner for attachment to a tank 3, or the equivalent. The tube 1 is preferably extended as at 2' above the flange 2, and is shown threaded at 60 the exterior. Where the tube is made for threaded engagement with the tank, the flange 2 may be formed similar to a nut, so as to permit its being engaged by a suitable wrench when desired. The lower end of the 65 tube is open, and the same being covered with a wire gauze 4, which may be reinforced and protected by the coarser wire gauze 5, thereby preventing the gauze 4 from being easily fractured. The tube is 70 also preferably formed with openings or apertures 6 thereabout near the bottom, which are covered with wire gauze 7. I have shown a flanged collar 8 arranged at the bottom, forming a convenient method of 75 securing the gauze parts to the tube, it being understood that the same may be soldered or otherwise secured in place. I also provide the tube with a series of openings or apertures 9, arranged adjacent the top, 80 this being covered by gauze 10, secured in place in any desired manner.

Arranged within tube 1 and spaced therefrom, is an inner tube 11, which is formed with a flange 12 of a size to closely fit the 85 inner wall or tube 1, the same being ribbed as at 14 if desired to provide spaces 13 above the flange and aid in maintaining the parts in position. The inner tube in the preferred construction is of such length that 90 the upper end 11' is adjacent the upper end 2' on the outer tube, and the partition 12 is so disposed that it is between the apertures 6 and apertures 9. The tube 11 is formed with a series of perforations or apertures 15, 95 therethrough, below the flange 12, the same

being of any desired size and shape, and the bottom is closed as at 16.

The closure for the tube consists of a neck part 18 arranged to be secured to the end of the outer tube, the same having one or more openings 19 through the same, and preferably recessed as at 20. Arranged on the part 18 is a cap 21, the same being chambered as at 22, and arranged to seat on the top 23 of part 18. As most clearly shown in Fig. 1, the part 21 is extended as at 24 to fit the recess 20, and internally flanged as at 25. Projecting through the part 18 and the part 21 is a tubular stem 27, the same being flanged as at 28 to overlie the flange 25. Arranged about the same is a spring 29, which bears against part 18 and the tubular part 39 carried by the tubular part 27, the spring normally maintaining the cap part 21 in the position shown in the drawings, so that the flange of the part is seated on the top or seat 23 of part 18. As I have mentioned, part 27 is tubular, the same having a chamber 30 communicating with the inlet duct 31, the part being formed with a valve seat 32.

Arranged on the end of stem 27 is a cap 33, which is chambered and provided with ducts 35, extending therefrom to the exterior, preferably at the sides. Within the chamber 30 is arranged a valve 36, which is normally maintained closed or against its seat 32, by the member 37 and spring 38, or equivalent means for the purpose. Part 39 is formed with a duct 40, the part being shouldered so as to support the end of the spring 38.

When it is desired to fill the tank to which the tube is applied, part 18 is removed, carrying with it the several parts described as forming the closure. The liquid may then be poured into the tank, from whence the same passes through the openings 15 into the space between the tubes, and through the wire gauzes 4, 5 and 7 to the interior of the tank. The air displaced within the tank passes through the wire gauze 10 and openings 9, through the spaces 13 between the tubes to the exterior. Any flame is prevented from entering the tank by the gauze 4, 5, 7 and 10, so that the tank cannot explode at the filler opening while the closure is removed for filling the tank, or when the closure is replaced. In case of any pressure within the tank for any reason whatever the same will be relieved by the raising of the part 21, the gas passing through the chamber out through the opening 19, and under the cap between the same and its seat. As the fuel is used up the forming of a vacuum within the tank is prevented by the admission of air through the openings 35, duct 31, past the valve 36, through the chamber 30,

and through 40 to the interior of the inner tube. The air may also pass up over the end 65 11 into chamber 13, and through the openings 9. The valve 36 prevents the escape of any fumes or gas from the interior of the tank. This is important, as in practically all garages the fumes from the fuel tank fill 70 the places, subjecting the same to possible fire and explosion. Of course where the tubes shown are not employed, the closure may be used in place of the ordinary cap, the pressure in the tank being relieved or air 75 admitted, etc., as described, but the tank, however, is not explosion proof.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned. 80 85

What I claim as new and desire to secure by Letters Patent is:—

1. In a tank closure device of the kind described, the combination of a part arranged to be detachably carried by the tank at the 90 filler opening thereof, said part forming at its top a valve seat, and with openings therethrough, a valve arranged on said seat, means for maintaining said valve in place, comprising a stem extended through said 95 part, and arranged to engage said valve, yieldable means for normally maintaining said valve in closed position, said stem provided with an opening therethrough with a valve seat on the interior thereof, a valve arranged in said stem, and arranged to permit the entrance of air through said stem from the exterior side of said cap, and prevent the escape of gas therethrough from the inner side of the cap, and an auxiliary cap arranged over the outer end of said stem provided with openings through the side walls thereof. 100 105

2. In a device of the kind described and in combination, a filler tube consisting of 110 inner and outer tubes spaced from one another, with a transverse partition in said space, said outer tube formed with openings above said partition, and below the same, the inner tube formed with openings below 115 said partition and a closure for said tubes arranged on the outer end of the outer tube, consisting of a part carried by the outer tube, with openings therethrough communicating with the inner tube, and with the space between the tubes above said partition, said part recessed upon its top face, a cap part arranged on said part of a size to extend beyond the openings through the part, said cap part formed with an extension fitting 120 125 said recess, and with a recess on the outer

side of the cap part with a flange formed at the bottom thereof, a tubular stem projecting through said parts and flanged at its upper end to overlie the flange on said cap, a 5 cap on the outer end of said stem of a size to form a chamber above the stem with openings communicating with said chamber formed in the side walls, said stem having a flange at its lower end, resilient means arranged 10 between said first mentioned cover part and said last mentioned flange for normally maintaining said cap part seated upon said other part, a check valve arranged within said stem movable toward the outer 15 end, to close the same, and means for normally maintaining said valve in closed position.

3. A tank closure of the kind described comprising the combination of a tube constructed for attachment to a tank and provided with a neck formed with a discharge port on the top face thereof, a cup shaped valve member arranged on said neck and normally covering said port, means for 20 guiding said valve member, and means for yieldingly maintaining said valve in closed position, comprising a tubular valve stem loosely carried by said valve member and extending through the said neck, and resilient means coöperating therewith and with the neck, and means for normally preventing the passage of gas through said tubular stem from the inner side of said neck.

4. A tank closure of the kind described comprising the combination of a tube constructed for attachment to a tank and provided with a neck formed with a discharge port on the top face thereof, the top face of 35 said neck forming at its periphery a valve seat, a valve member having a depending peripheral flange to engage said seat and a depending central apertured part resting on said neck, and means for yieldingly maintaining said valve in closed position, comprising 40 a tubular valve stem loosely carried by the valve member, said stem projecting through said central aperture and having a spring abutment adjacent its lower end, and a spring interposed between said 45 abutment and the inner surface of said neck.

5. A tank closure of the kind described comprising the combination of a tube constructed for attachment to a tank and provided with a neck formed with a discharge 55 port on the top face thereof, the top face of said neck forming at its periphery a valve seat, a valve member having a depending peripheral flange to engage said seat and a depending central apertured part resting on 60 said neck, and means for yieldingly maintaining said valve in closed position, comprising a tubular valve stem loosely carried by the valve member, said stem projecting

through said central aperture and having a spring abutment adjacent its lower end, a 65 spring interposed between said abutment and the inner surface of said neck, the hollow valve stem having a valve seat, and a spring supported valve within the valve stem to engage said seat. 70

6. A tank closure of the kind described comprising the combination of a tube constructed for attachment to a tank and provided with a neck formed with a discharge port on the top face thereof, the top face of 75 said neck forming at its periphery a valve seat, a valve member having a depending peripheral flange to engage said seat and a depending central apertured part resting on said neck, and means for yieldingly maintaining said valve in closed position, comprising a tubular valve stem loosely carried by the valve member, said stem projecting through said central aperture and having a spring abutment adjacent its lower end, a 80 spring interposed between said abutment and the inner surface of said neck, the hollow valve stem having a valve seat, and a spring supported valve within the valve stem to engage said seat, said last mentioned 85 valve acting normally to prevent the passage of gas through said tubular stem from the inner side of the neck. 90

7. A tank closure of the kind described comprising a tubular wall having a peripheral opening adjacent the top thereof and being open at the top, a closure neck for said end opening having a depending peripheral flange overlying the outer surface of said tubular wall and a depending annular central flange, said neck having a series of openings in the top surface thereof, and said top surface adjacent the periphery forming a valve seat, a valve member having a peripheral depending flange to engage 95 the valve seat, and an annular central depending flange to engage the neck at a point within the openings in the neck, and means for normally retaining said valve on its seat comprising a tubular valve stem engaging the outer surface of the valve and projecting centrally through the valve and closure neck, and a spring interposed between said stem and the under surface of 100 said neck. 110

8. A tank closure of the kind described comprising a tubular wall having a peripheral opening adjacent the top thereof and being open at the top, a closure neck for said end opening having a depending peripheral flange overlying the outer surface of 105 said tubular wall and a depending annular central flange, said neck having a series of openings in the top surface thereof, and said top surface adjacent the periphery forming a valve seat, a valve member hav- 115

4

ing a peripheral depending flange to engage the valve seat, and an annular central depending flange to engage the neck at a point within the openings in the neck, and means 5 for normally retaining said valve on its seat comprising a tubular valve stem engaging the outer surface of the valve and projecting centrally through the valve and closure neck, and a spring interposed between said 10 stem and the under surface of said neck, said tubular valve stem having an internal valve seat, and a spring held valve within the

tubular valve stem to engage said internal valve seat to prevent the passage of gas through said tubular stem from the inner 15 side of said neck.

In testimony whereof I have hereunto signed my name in the presence of two subscribing witnesses.

LOUIS KESSLER.
